EX

OR D 16,381

DESIGN.

—o—
M. EISNER & J. MENDELSON.

STAND.

No. 16,381.

Patented Nov. 10, 1885

UNITED STATES PATENT OFFICE.

MORITZ EISNER AND JOSEPH MENDELSON, OF PHILADELPHIA, PA.

DESIGN FOR A STAND.

SPECIFICATION forming part of Design No. 16,381, dated November 10, 1885.

Application filed August 27, 1885. Serial No. 175,519. Term of patent 3½ years.

To all whom it may concern:

Be it known that we, MORITZ EISNER and JOSEPH MENDELSON, both citizens of the United States, residing in the city and county of Philadelphia, State of Pennsylvania, have invented and produced a new and original Design for a Stand, of which the following is a specification, reference being had to the accompanying photographic illustrations, forming part thereof.

The leading feature of our design is the representation of a stair-shaped stand having rings and twisted necks.

A represents a wire stand the sides whereof are stair-shaped. B represents rows of horizontally-arranged rings, which extend from one side of the stand to the other. Between the rings of the rows B are twisted necks D.

We have shown and described in an application, Serial No. 175,514, filed August 27, 1885, 20 a design for a stand having stair-shaped sides, rings B, top cross-bar, D, and bottom cross-bar, F, and also said parts with a fork, E, and feet G, which we do not claim herein; but

What we do claim is—

A design for a stand having stair-shaped side pieces, A, rings B, and twisted necks D, substantially as shown.

MORITZ EISNER.

JOSEPH MENDELSON.

Witnesses as to Eisner:

JOHN A. WIEDERSHEIM,
A. P. GRANT.
